UNITED STATES PATENT OFFICE.

WILLIAM PATTERSON, OF ONEONTA, NEW YORK.

IMPROVEMENT IN STOVE-PIPE SHELVES.

Specification forming part of Letters Patent No. 140,788, dated July 15, 1873; application filed December 6, 1872.

To all whom it may concern:

Be it known that I, WILLIAM PATTERSON, of Oneonta, in the county of Otsego and State of New York, have invented certain Improvements in Stove-Shelves, of which the following is a specification:

This invention consists in the peculiar construction of the attachments or supports of the stove-shelf and the mode of fastening the whole to the stove-pipe.

Figure 1 is a plan of the stove-pipe with the shelves attached, showing the shelves in different positions. Fig. 2 is a side elevation of the pipe with the attachments or supports fastened thereto by a single wire. Fig. 3 shows the pipe and one support. Fig. 4 shows the under side of the shelf.

The shelf S is made as thin and light as possible—somewhat thicker at c, where it rests upon the band b when attached to the stove-pipe. The smaller end is perforated at

e so as to receive the pivot p on the under side of the brace r; and, when placed in its proper place, the shelf rests upon the band b of the support or attachment A. The support or attachment A consists of a concave plate, to which is attached the band b, brace r, and pivot p, and is held firmly against the pipe D by the wire W—the wire W being fastened by means of an eye in one end and a hook at the other end. The shelf or shelves are easily detached, and can also be swung around out of the way. The two shelves may be used separately or together.

What I claim as my invention, is—

The arrangement and combination of the supports A A, shelves S S, and wire W, substantially as shown and described.

WILLIAM PATTERSON.
